UNITED STATES PATENT OFFICE.

HIRAM PERCY MAXIM, OF HARTFORD, CONNECTICUT.

MUFFLER.

Application filed November 21, 1921. Serial No. 516,815.

To all whom it may concern:

Be it known that I, HIRAM PERCY MAXIM, a citizen of the United States, residing at Hartford, in the county of Hartford and 5 State of Connecticut, have invented new and useful Improvements in Mufflers, of which the following is a specification.

This invention relates to mufflers or silencers and while capable of general application it is more particularly adapted for use in connection with pneumatic machinery such as air drills, hoists, compressors or the like for silencing either the exhaust or the intake thereof.

One object of the invention is to provide a muffler adapted to encircle a tubular conductor carrying the air or other sound propagating medium and to receive said medium directly from a lateral exhaust port 20 in the wall of said tube.

Another object of the invention is to provide a muffler having one or more of its parts constructed and arranged to cooperate readily with additional parts of similar construction to increase the capacity of the muffler.

Further objects of the invention are to provide a muffler having a minimum number of component parts, to provide a muffler 30 of unusually simple and rugged construction, and to provide a reliable and efficient muffler at a low cost of manufacture.

To the accomplishment of these objects and such others as may hereinafter appear, 35 the invention comprises the features of construction and arrangements of parts herein-after described and particularly pointed out in the appended claims.

In the drawings—

Fig. 1 is a view, partially in longitudinal section and partially in side elevation, of a muffler constructed in accordance with the present invention and embodying certain preferred features of construction adapting 45 it for use in connection with a tubular body or conductor having a lateral exhaust or intake port;

Figs. 2 and 3 are views similar to Fig. 1 and show mufflers which embody certain 50 preferred features of construction common to the muffler shown in said figure but which have greater capacity so that they are capable of muffling the noise of a more powerful exhaust or intake.

Referring to Fig. 1 of the drawings, a 55 muffler 5 encircles the outer tubular casing

6 of a pneumatic drill and encloses a lateral exhaust port 7 in said casing. The muffler 5 comprises two castings in the form of annular end plates or heads 8 and 9, the 60 plate 8 having a hub 10 upon its outer face and a plurality of concentric annular ribs or flanges 11 projecting axially from its inner face, while the plate 9 has a hub 12 upon its outer face and a plurality of concentric annular ribs or flanges 13 projecting 65 axially from its inner face in staggered relation to the corresponding ribs 11 of the plate 8. The hubs 10 and 12 are adapted to receive and fit tightly upon the drill casing 70 75 75 and the plate 8 is adapted to be rigidly secured to said casing by means such as a key or pin 14, extending through the hub of said plate and through a keyway in the drill casing. The two end plates 8 and 9 are assembled on the drill casing with the annular ribs of each plate interposed between the adjacent ribs of the other plate and with the edge face of each rib spaced 80 from the inner face of the opposed end plate. The end plates are secured in the relative positions above specified by means of a plurality of tie-bolts one of which is shown at 15, this bolt extending in an axial direction through the end plates and having 85 a head bearing against the outer face of the end plate 8 and a nut 16 threaded upon the opposite end of the bolt and bearing against the outer face of the end plate 9. The tie-bolts 90 may be provided with spacing collars 17 for spacing the edge faces of the annular ribs 11 and 13 from the opposed end plates.

By virtue of the above described construction and arrangement of the end plates and their ribs there is provided between 95 said plates a series of annular concentric chambers 18 which are interconnected so as to form a continuous tortuous passage radiating from the drill casing in all directions perpendicular to its axis. The innermost chamber 18 registers with the exhaust port 7 to receive therefrom the exhaust air and the sound waves issuing from the drill casing. From the innermost chamber 18 the air and sound waves pass outwardly in a 100 zig-zag course through the tortuous passage between the end plates and are finally discharged through an annular port 19 in the outer periphery of the muffler. As the sound waves travel through the abrupt 105 turns of the above described muffler passage, they are broken up so that the noise is 110

deadened or muffled before they emerge through the port 18. To further assist in deadening the noise of the exhaust the invention also contemplates covering or "upholstering" the walls of the tortuous passage with material such as powdered asbestos which will tend to prevent reflection of the sound waves.

The above described muffler is composed of a minimum number of parts which are adapted to be compactly arranged to produce an effective muffler of relatively small size. The parts of the muffler are preferably made of cast metal and are of such design that they may be economically manufactured and readily assembled. Furthermore, the muffler is of particularly rugged construction and well adapted to withstand the rough handling incident to the use of air drills or the like.

In Fig. 2 is shown a muffler 20 of greater capacity than the muffler 5 hereinbefore described. The muffler 20 is applied to a tubular drill casing 21 which is similar to the drill casing upon which the muffler 5 is mounted but which is provided with a lateral exhaust port 22 which is of greater area than the port 7 shown in Fig. 1 to permit the escape of a more powerful exhaust. As shown, the port 22 is elongated longitudinally of the drill casing and the muffler 20 is of greater axial width than the muffler 5 so as to cover the longer port. The muffler 20 is composed of three castings comprising an annular end plate 23, a second annular end plate 24 and an intermediate annular member 25. The end plate 23 is a duplicate of the end plate in Fig. 1, being provided with concentric annular ribs 11 having the same construction and arrangement as the corresponding ribs of the end plate 8. The end plate 24 is similar to the end plate 23 and the concentric annular ribs carried by the plate 24 have exactly the same construction and arrangement as the ribs of the plate 23. The two end plates 23 and 24, however, are arranged in reversed positions upon the drill casing with their ribbed faces opposed to each other. The intermediate annular member 25 is provided with ribs 26 projecting from its opposite side faces, these ribs being arranged in staggered relation to the ribs of the end plates 23 and 24 when said member and end plates are positioned upon the drill casing. The three muffler members 23, 24 and 25 are adapted for assembly with the ribs 26 interposed between and spaced from the ribs of the members or plates 23 and 24, and the three members are held in assembled relation by means of tie-bolts 27. Suitable means such as spacing collars 27' may be provided for spacing said members laterally so that the edge faces of the ribs 26 will be spaced from the inner faces of the respective end plates 23 and 24.

and the edge faces of the ribs upon said end plates will be spaced from the adjacent side faces of the intermediate member 25. Thus a tortuous passage is formed on either side of the intermediate muffler member 25 these passages being the same as the tortuous passage provided in the muffler 5. By reason of the fact that the inner diameter of the member 25 is greater than the outer diameter of the drill casing the two tortuous passages are connected adjacent the periphery of the drill casing to form a central annular chamber registering with the port 22 to receive the exhaust air and the sound waves. The two muffler passages terminate in annular discharge ports 28 and 29 in the periphery of the muffler at opposite sides of the intermediate member 25. A pin 30 extends through the hub of the plate 23 to secure the above described muffler to the drill casing.

The muffler 31 shown in Fig. 3 is of still greater capacity than the muffler 20 and is applied to a drill casing having a lateral exhaust port 32 of greater area and length than the port 22 and thus adapted to permit the escape therethrough of a more powerful exhaust. The muffler 31 comprises five ribbed members 33, 34, 35, 36 and 37, the members 33, 34 and 37 being duplicates of the members 23, 24 and 25, respectively, of the muffler 20 shown in Fig. 2. The member 36 is also a duplicate of the member 25 of the muffler 20 and the member 35 is similar to the members 34 and 36 but is provided with four ribs upon each side instead of three ribs as in said members. The members of the muffler 31 are assembled in the same spaced relation as that described in connection with Fig. 3 and they may be similarly secured together in spaced relation and similarly fastened to the drill casing. When the five muffler members are assembled as shown in Fig. 3, four tortuous muffler passages are provided which lead outwardly from a common central chamber which registers with the port 32.

From the foregoing description it will be seen that the capacity of the muffler shown in Fig. 1 may be doubled by substituting for the end plate 9 another end plate which is or may be a duplicate of the end plate 8 and by interposing between the end plates a third member such as the member 25. It will also be seen that the capacity of a muffler constructed as shown in Fig. 2 may be doubled by merely interposing between one of its end members and the adjacent member two other muffler members such as those shown at 35 and 36 in Fig. 3. It is obvious that to construct a muffler of still greater capacity it will be necessary only to provide more intermediate muffler members in the assembly. Thus by keeping in stock a supply of the several different forms of muffler members herein described, a manufacturer is en-

abled to readily construct a muffler of any required capacity simply by assembling the required number of muffler members in their proper relative positions and securing the 5 assembled members together by tie-bolts of the proper length.

The invention has been disclosed herein for illustrative purposes in its preferred embodiment and also with the aid of certain 10 modifications thereof but it is to be understood that the scope of the invention is defined by the appended claims rather than by the foregoing description.

What I claim is:

- 15 1. A muffler comprising a plurality of annular members adapted for assembly in side by side spaced relation upon a tubular conduit for intake or exhaust gases, said members each having a plurality of concentric annular ribs projecting from its face into staggered relation with similar ribs upon the opposed face of an adjacent member to provide one or more continuous tortuous passageways radiating in all directions perpendicular to the axis of said conduit, said conduit having a lateral port opening into said radiating passageway or passageways, and means for securing said members to said conduit with the members and ribs arranged 20 as specified.
- 25 2. A muffler comprising a plurality of annular members adapted for assembly in side by side spaced relation upon a tubular conduit for intake or exhaust gases, said members each having a plurality of concentric annular ribs projecting from its face into staggered relation with similar ribs upon the opposed face of an adjacent member to provide one or more continuous tortuous passageways radiating in all directions perpendicular to the axis of said conduit, said conduit having a lateral port opening into said radiating passageway or passageways, and means for securing said members to said conduit with the members and ribs arranged 30 as specified.
- 35 3. A muffler comprising a plurality of annular members adapted for assembly in side by side spaced relation upon a tubular conduit for intake or exhaust gases, said members each having a plurality of concentric annular ribs projecting from its face into staggered relation with similar ribs upon the opposed face of an adjacent member to provide one or more continuous tortuous passageways radiating in all directions perpendicular to the axis of said conduit, said conduit having a lateral port opening into said radiating passageway or passageways, and means for securing said members to said conduit with the members and ribs arranged 40 as specified comprising tie bolts and spacing collars.
- 45 4. A muffler comprising a plurality of annular members adapted for assembly in side by side spaced relation upon a tubular conduit for intake or exhaust gases, said members each having a plurality of concentric annular ribs projecting from its face into staggered relation with similar ribs upon

the opposed face of an adjacent member to 55 provide one or more continuous tortuous passageways radiating in all directions perpendicular to the axis of said conduit, said conduit having a lateral port opening into said radiating passageway or passageways, 60 a hub upon one of said members, means for securing said members together with the members and ribs arranged as specified, and means for securing said hub to said conduit. 65

4. A muffler comprising an annular member adapted to fit tightly upon the outside of a cylindrical conductor provided with a lateral port, a plurality of concentric annular ribs projecting in axial directions from 70 one face of said member, a second end member similar to the first member and having the same arrangement of ribs thereon and cooperating with the first member to provide a central muffler chamber for communicating with said port, one or more intermediate muffler members interposed between the first and second members and each having a plurality of concentric ribs projecting from opposite sides thereof adapted to be 75 interposed between and spaced from the ribs of the next adjacent member, and means for securing said members together with the ribs arranged as specified and also with the inner face of each member spaced from the 80 ribs of the opposed member and means for securing the whole structure to said conductor.

5. A muffler comprising a plurality of annular members held in assembled relation, 90 the outermost members of which are adapted to fit tightly upon a tubular conduit carrying intake or exhaust gases to provide an annular central chamber around said conduit with which a lateral port in said conduit communicates, each of said annular members having a plurality of concentric annular ribs projecting from its face into staggered relation with similar ribs upon the opposed face of an adjacent member to 95 provide one or more continuous tortuous passageways radiating in all directions from said central chamber, and means for retaining said annular members in assembled relation as specified. 100

In testimony whereof I have affixed my signature.

HIRAM PERCY MAXIM.
